UNITED STATES PATENT OFFICE.

LOUIS M. BROWN, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

WORK-POSITIONING MEANS.

1,319,266.

Specification of Letters Patent. Patented Oct. 21, 1919.

Application filed May 26, 1915. Serial No. 30,580.

To all whom it may concern:

Be it known that I, Louis M. Brown, a citizen of the United States, residing at Beverly, in the county of Essex and State 5 of Massachusetts, have invented certain Improvements in Work-Positioning Means, of which the following description, in connection with the accompanying drawings, is a specification, like reference characters on the 10 drawings indicating like parts in the several figures.

This invention relates to shoe machinery and particularly to work positioning means or apparatus, and is herein shown as embodied in a construction designed for use 15 in a lasting machine of the type shown and described in prior United States Letters Patent No. 1,018,477, granted Feb. 27, 1912, on application of Matthias Brock. 20 One object of the invention is to improve the machine of said patent by facilitating the unjacking of shoes and eliminating danger of damaging high-toed shoes while they are being retracted in the machine during 25 the unjacking operation.

A feature of the invention consists in a novel construction and arrangement of mechanism constituting a work rest, with provision for relief of pressure between the work 30 and the rest to facilitate withdrawal of the machine. In the illustrated embodiment of the invention the work rest comprises a supporting member and a work engaging member hereinafter termed a face pad which is 35 guided on the supporting member to move rearwardly and downwardly with reference to the position of a shoe supported bottom upward. The guiding means is constructed and arranged to provide a stable condition 40 of the face pad in its elevated position and as herein shown the face pad is supported to have a substantial range of backward movement on the supporting member before it reaches a point where it is allowed to 45 descend. An advantage in this construction is that the work rest in its normal condition affords an effective support against downward pressure on the bottom of the shoe.

A further feature of the invention consists in coöperating guiding means on the supporting member and on the face pad constructed and arranged to prevent tipping movement of the face pad. These guiding means are shown as consisting of grooves

cut in the side faces of the supporting member and studs projecting into the grooves and carried by depending side flanges of the face pad. A further feature of the invention consists in means for returning the face pad to normal relation to the supporting means and retaining it normally in such relation.

These and other features of the invention, including certain details of construction and combinations of parts, will now be described 65 with the aid of the accompanying drawings, which show an illustrative embodiment of the invention, and will then be pointed out in the claims.

Figure 1 in the drawings is a side elevation, partly in section, of so much of a lasting machine equipped with this invention as is needed for use in explaining the invention, and

Fig. 2 is a perspective view of the toe rest 75 showing the face pad and its supporting member separated relatively in order better to illustrate the construction of each.

The work holding means of the illustrated lasting machine includes a toe support A on 80 which the toe portion of the shoe rests and a jack comprising a heel pin B which enters the heel pin hole of the last and is movable with the heel lasting mechanism to carry the shoe toward and over the toe rest and 85 reversely to free the shoe from the rest and the toe embracing mechanism, herein shown as wipers, in unjacking the shoe and presenting it in position to be removed from the machine. The toe rest occupies a de- 90 pressed position at the time the shoe is moved forward and is then raised to hold the shoe for the lasting operation, this elevation being produced by a vertically mov- 95 able slide 2 on which the toe rest stem 3 is supported and which has a roll standing on the periphery of a cam 4 on cam shaft 5. In the jacking operation, wherein the toe rest is elevated and the heel band is closed on the shoe, the spring 6 is put under ten- 100 sion and in the unjacking operation that spring is released and effects the rearward movement of the heel pin to carry the shoe backwardly to position to be removed. The cam 4 supporting the toe rest is also turned 105 in the unjacking operation to allow the toe rest to descend but in practice the spring 6 acts to draw the heel pin and the shoe back-

wardly before the toe rest descends far enough to clear the shoe and, particularly if the last has a prominent toe, the shoe drags over the rest. The mechanism and the general organization of the machine thus far briefly discussed are the same as fully shown and described in said prior patent.

In accordance with the present invention there is provided for shoe making apparatus, and incorporated in the type of lasting machine shown in said prior patent, a toe rest comprising the supporting member 10 and the face pad 12. The supporting member is a head formed on the stem 3 and its top face includes, as best shown in Fig. 2, a horizontal face 11, a downwardly and rearwardly inclined face 13 extending from the rear end of the face 11, a second horizontal face 14 extending from the lower end of the inclined face 13, and a second inclined face 15 extending from the rear end of the face 14. The face pad comprises a cushion and a body portion which is formed with faces which are parallel to and coöperate with the faces 11, 13, 14 and 15, and said pad is adapted to slide on the supporting member rearwardly in a horizontal plane, see Fig. 1, through the length of the horizontal faces 11 and 14 and then to slide down the incline of faces 13 and 15 to the dotted line position shown in Fig. 1. A spring 16 located in a slot in the supporting member 10 and extending from an anchor therein to an anchor in face pad 12 holds the face pad usually in full line position, Fig. 1, and returns it automatically to the higher plane and to its normal longitudinal relation to the supporting member 10 when the shoe has been disengaged from the face pad. The face pad is restrained from lateral displacement relatively to the supporting member by flanges depending from the pad and embracing said member. The pad is further guided, and is restrained from tipping movement on said member, by studs 17, 18 which project from the flanges into guide grooves 20 cut into the opposite side faces of the supporting member and extending parallel to the faces 11, 13, 14 and 15 on the top of said member. The faces 11 and 14 provide a normally elevated position for the face pad of the toe rest in which it is maintained at the same elevation while it may slide longitudinally of the machine as may be required during the operation of the machine, it being understood that the toe embracing mechanism is movable lengthwise of the shoe and that the stem 3 of the toe rest is operatively connected with said mechanism for adjustment therewith lengthwise of the machine for shoes of different lengths. The inclined faces and particularly the upper walls of the grooves 20, guide and wedge the face pad downwardly as it is drawn rearwardly with the shoe and into a plane where the shoe can

slide off from the face pad without objectionable resistance or danger of abrasion of the shoe leather.

It is to be understood that the term "face pad" is not used herein in a sense imposing any limitation with respect to the character or construction of that part of the rest which contacts with the work, and that such part may be variously constructed consistently with the purposes and objects of the invention.

Having explained the nature of this invention and described an illustrative construction embodying the same, I claim as new and desire to secure by Letters Patent of the United States:

1. Apparatus of the class described, having, in combination, a toe rest comprising a supporting member and a face pad, and guiding means constructed and arranged to permit movement of the face pad on the supporting member and to cause such movement to take place in a horizontal plane to a definite point and then in a plane inclined downwardly and rearwardly from said plane.

2. Apparatus of the class described, having, in combination, a toe rest comprising a supporting member and a face pad; and coöperating guiding means which includes a horizontal face of substantial length on the supporting member and a downwardly and rearwardly inclined face extending from the rear end of the horizontal face, and coöperating parallel faces on the face pad.

3. Apparatus of the class described, having, in combination, a toe rest comprising a supporting member and a face pad; and coöperating guiding means which includes a horizontal face of substantial length on the supporting member and a downwardly and rearwardly inclined face extending from the rear end of the horizontal face, and a second horizontal face on the supporting member, and coöperating parallel faces on the face pad.

4. Apparatus of the class described, having, in combination, a toe rest comprising a supporting member and a face pad; and guiding means constructed and arranged to permit movement of the face pad on the supporting member and comprising guide grooves cut into the side faces of the supporting member, flanges depending from the face pad, and guiding means extending from the flanges into said grooves.

5. Apparatus of the class described, having, in combination, a toe rest comprising a supporting member and a face pad; and guiding means constructed and arranged to permit movement of the face pad on the supporting member in a horizontal plane and to provide a normal elevated position of the face pad in which it can move horizontally and to permit downward movement of

the face pad relatively to the supporting member in response to horizontal displacement carried beyond a definite point.

6. Apparatus of the class described, having, in combination, a work rest comprising a work engaging member constructed and arranged to move downwardly in response to movement of the work thereon in a horizontal plane beyond a definite point, and means for holding said member normally against movement beyond that point.

7. Apparatus of the class described, having, in combination, a work rest comprising a supporting member having on its top a horizontal guide face, a downwardly and rearwardly inclined guide face at the rear end of the horizontal face, a second horizontal guide face at the rear end of the inclined face and a second inclined face at the rear end of the second horizontal face; and a face pad movable longitudinally of said guide faces and confined against movement transversely thereof and having horizontal guide faces arranged to slide on said horizontal faces of the supporting member.

8. Apparatus of the class described, having, in combination, a work rest comprising a supporting member having in its vertical side faces guide grooves comprising horizontal portions and downwardly and rearwardly inclined portions at the rear of the horizontal portions; and a face pad having depending flanges provided with means to coöperate with said guide grooves to cause the face pad when moved on the supporting member to follow first the horizontal and then the inclined portions of said guide grooves.

9. Apparatus of the class described, having, in combination, toe embracing mechanism movable longitudinally of the machine, and shoe supporting means including a toe rest having a face pad and a supporting member connected with the toe embracing mechanism to be moved lengthwise of the shoe thereby, and a connection between the face pad and its supporting member constructed to permit movement of the supporting member with the toe embracing mechanism for a limited distance while sustaining the face pad in a plane and to permit the face pad to descend to a lower plane upon further relative movement of the embracing mechanism and supporting member on the one hand and the face pad on the other hand.

10. Apparatus of the class described, having, in combination, toe embracing mechanism movable longitudinally of the machine, and shoe supporting means including a toe rest having a face pad and a supporting member connected with the toe embracing mechanism to be moved lengthwise of the shoe thereby, a connection between the face pad and its supporting member con-

structed to permit movement of the supporting member with the toe embracing mechanism for a limited distance while sustaining the face pad in a plane and to permit the face pad to descend to a lower plane 70 upon further relative movement of the embracing mechanism and supporting member on the one hand and the face pad on the other hand, and means to return the face pad automatically to the higher plane and 75 to its normal relation to the supporting member when the shoe is disengaged from the face pad.

11. In apparatus of the class described, a work rest comprising a work engaging member and guiding means constructed to permit movement of said member in a direction at an angle to its work engaging face in consequence of frictional drag of the work on said member. 80

12. In apparatus of the class described, a work rest comprising a work engaging member and supporting means arranged for relative movement in response to frictional drag of the work on said member, and wedging means arranged to operate in said relative movement of the parts to move said member in a direction at an angle to its work engaging face to relieve its pressure on the work. 90

13. In apparatus of the class described, a work rest comprising a work engaging member and a support connected for relative movement against yielding resistance in response to frictional drag of the work on 100 said member, the connection between said member and its support being constructed to cause the member to move relatively to the support in a path inclined to that portion of the surface of the work which it 105 engages.

14. In apparatus of the class described, a work rest comprising a work engaging member and a support connected for relative movement against yielding resistance in response to frictional drag of the work on 110 said member, the connection between said member and its support being constructed to cause such relative movement to take place first in a direction substantially or approximately parallel to the work engaging face of said member and then in a direction at an angle to said face. 115

15. In apparatus of the class described, a work rest comprising a support and a 120 work engaging member movably mounted on said support, and guiding means constructed to permit an initial movement of said member relatively to the support in a direction substantially or approximately 125 parallel to its work engaging face followed by a movement in a direction at an angle to said face.

16. In apparatus of the class described, a shoe rest comprising a member for engaging 130

- a shoe on the top of the forepart, and means for supporting said member in a normal position in which it is substantially rigid against pressure on the bottom of the shoe 5 while permitting the member to be moved by lengthwise movement of the shoe into a position in which it is permitted to yield in a direction transverse to the plane of the shoe bottom.
- 10 17. In apparatus of the class described, a shoe rest comprising a member for engaging a shoe on the top of the forepart, means for supporting said member in a normal position in which it is substantially 15 rigid against pressure on the bottom of the shoe while permitting relative movement between the member and its supporting means lengthwise of the shoe, and means arranged to operate upon the member following a determinate extent of such relative movement to force the member away from the shoe in a direction transverse to the lengthwise dimension of the shoe.
18. In apparatus of the class described, 20 a shoe rest comprising a member arranged to engage the surface of a shoe on the top of the forepart and a support on which said

member is mounted, said support and member being connected for relative movement lengthwise of the shoe in response to frictional drag between the member and the shoe, and means operative in said relative movement of the parts to cause the shoe engaging member to receive a component of movement in a direction at an angle to the portion of the surface of the shoe which it engages to relieve its pressure on said surface.

30 19. In apparatus of the class described, a shoe supporting jack, a work rest arranged to engage the top of the forepart of a shoe supported on said jack, the jack and work rest being relatively movable lengthwise of the shoe, and means arranged to operate in consequence of frictional drag of the shoe 35 on the work rest to cause the shoe engaging portion of said rest to be moved in a direction at an angle to the plane of the shoe bottom and away from the top of the forepart of the shoe to relieve its pressure on the 40 50 shoe.

In testimony whereof I have signed my name to this specification.

LOUIS M. BROWN.
